SEPARATION OF WAX FROM
HYDROCARBON OILS

Robert E. Manley, Port Arthur, Tex., assignor to
The Texas Company, New York, N. Y., a corporation of Delaware

Application April 20, 1931, Serial No. 531,648

1 Claim. (Cl. 196—19)

This invention relates to the separation or extraction of paraffin wax from hydrocarbon oils, and more particularly to an improved method of separating wax from wax-bearing mineral oils for the production of low cold test lubricating oils.

The invention broadly contemplates the process of separating solid hydrocarbons from liquid hydrocarbons, comprising dissolving wax-containing mineral oil in a solvent possessing the properties of dissolving all the hydrocarbons contained therein at elevated temperature and having a selective solvent action between the liquid hydrocarbons and solid hydrocarbons at relatively low temperatures, chilling the liquid solution to a point where the solid hydrocarbons separate out, then filtering the chilled solution to remove the liquid hydrocarbons in solution from the separated solid hydrocarbons and washing the resulting filter cake of separated solid hydrocarbons, *in situ*, with cold solvent liquid to remove entrained or adhering oil.

In my prior application, Serial No. 233,565, filed November 16, 1927, I have described a process for dewaxing hydrocarbon oils by filtration of a chilled mixture of solvent and oil in the presence of a filter-aid material and wherein the resulting cake of solid hydrocarbons and filter-aid material is subjected to washing by forcing an oil solvent through the material deposited on the filter at such temperature that no substantial quantity of the waxy constituents may be dissolved therein, whereby a substantially complete separation of oil from the waxy constituents is obtained.

My present invention comprises an improvement to the method of dewaxing oils disclosed in the aforesaid application, and has particular reference to the treatment of the slack wax cake to effect complete removal of the adhering and retained oil, and also produce substantially oil-free slack wax which is entirely satisfactory for sweating for the production of high melting point wax. The invention has particular reference to the so-called solvent type of dewaxing process wherein, for example, the wax-bearing oil is mixed with acetone and benzol in such a ratio to each other and to the said fraction that the acetone and benzol together at temperatures of approximately 100° F. have substantially complete solvent action on the wax-bearing oil and at temperatures of —5° F. and below, have substantially complete solvent action on the liquid hydrocarbons but substantially no solvent action on the solid hydrocarbons in said

fraction, and upon removal of the solid hydrocarbons and the acetone and benzol, such oil has a cold test substantially the same as the temperature of the mixture at the time of the removal of the solid hydrocarbons, and following which the mixture is cooled to a temperature at which substantially all of the solid hydrocarbons are precipitated and the cooled mixture then subjected to filtration to separate the solid hydrocarbons so precipitated.

The filter cake of slack wax or petrolatum formed in the filtration methods of dewaxing wax-bearing hydrocarbon oils usually contains substantial proportions of liquid hydrocarbons which are not only valuable as lubricating oil but also when allowed to remain even in fairly small amounts in the wax cake inhibit and prevent the satisfactory sweating of the wax cake. The complete removal of this adhering oil, particularly in the case of wax filter cakes formed in the dewaxing of hydrocarbon oils by means of a selective solvent such as acetone and benzol, and where the resulting cake does not contain filter aid material, has never been realized heretofore. As is usual in filtering operations of this type when a filter cake of desired thickness has been built up on the filtering surfaces, it is customary to stop the flow of liquid into the filter and displace the contents of the filter shell, either by draining out or by blowing back with gas or air and then subjecting the cake to washing with a suitable washing liquid. However, during the draining of the filter or blowing back of the filter shell contents, and which includes the body of liquid immediately adjacent the cake, substantial portions of the cake may fall completely away from the filtering surface, or the cake may develop cracks so that during the subsequent cake washing step the washing liquid short circuits through the cracks in the cake or through those portions of the filtering surfaces from which the cake has fallen, thus militating against the uniform and effective washing of the filter cake.

An important object of my invention comprises an improvement in the method of carrying out the filtering step. The chilled mixture of liquid hydrocarbons dissolved in a solvent together with solid hydrocarbons suspended therein is introduced to a filter to remove the solvent and dissolved oil while depositing the solid hydrocarbons on the filtering surface in the form of a cake. As soon as a filter cake of desired thickness has been obtained the introduction of the filtering mixture to the filter is

stopped and the introduction to the filter of a solvent wash liquid is immediately started without a cessation of flow of liquid through the filter cake and filtering surfaces. The change 5 in liquid flow from solvent and dissolved hydrocarbon liquid to pure solvent washing liquid is effected in such a manner as to maintain a continual plus liquid pressure on the filter cake during the final stages of filtration as well as 10 throughout the washing period. In this way there is a body of liquid continually in contact with the entire surface of the cake exerting a positive pressure thereover to facilitate its complete adherence to the filtering surface so that it 15 does not become partially dislodged therefrom prior to or develop cracks during the initial stages of the washing period and, consequently, since short circuiting of the solvent wash liquid is thus prevented, the filter cake is subjected to 20 a complete and effective washing action, thereby resulting in the obtaining of a substantially oil-free wax cake.

Reference may be made to the accompanying drawing which illustrates apparatus suitable for 25 practicing the method of my invention.

This apparatus may comprise a charging tank 1 from which the dilute wax-bearing mixture is introduced to a chiller 2 wherein it may be chilled to a temperature of around 0° F. or below. From the chiller, the oil is conducted 30 through a pipe 3 having a valve 4 into the interior of a filter 5.

The filter 5 is advantageously of the rotating leaf type and adapted for pressure filtration. 35 It comprises an insulated shell containing a filtering element comprising a series of hollow leaves 6 supported on, and integral with, a hollow rotating shaft 7. In operation, the solids are deposited on the exterior surfaces of the 40 hollow leaves while the filtrate passes therethrough into the interior of the leaves. From the interior of each leaf, the filtrate flows into the hollow shaft 7 from which it is discharged through a filter valve 8.

45 From the valve 8, the filtrate is discharged through a pipe 9 having a valve 10.

Solvent liquid for washing the cake is conducted from a tank 11 through a pipe 12, having a valve 13, into the interior of the filter 5. This 50 wash solvent, together with the oil displaced from the filter and filter cakes, is removed from the filter through the hollow shaft 7 in a manner similar to that of the filtrate already described. However, the wash liquid may be removed from the valve 8 through a separate pipe 14 having a valve 15.

During filtration the filter shell is maintained entirely full of filtering mixture so that the rotating filter leaves 6 are completely submerged. 60 As the thickness of the cake being formed on the exterior surfaces of the filter leaves 6 increases, due to the resulting increasing resistance to flow of fluid through the cake, the pressure within the filter shell, as indicated on a pressure gauge 16, also increases, reaching a given maximum point when a cake of desired thickness has been formed.

At this point, the valve 4 is gradually closed 70 while the valve 13 is simultaneously open so as to maintain a substantially constant inflow of fluid to the interior of the filter shell and thus continually maintain a plus-pressure therewithin.

The inflowing wash solvent liquid mingles with 75 the liquid contents of the filter shell, and is

displaced through the filter cakes into the hollow shaft 7, from which it is discharged from the filter. The flow of wash solvent into the filter is continued until all the oil remaining in the filter shell and adhering to the cakes is displaced. Thereupon, the valve 13 is closed, and cold gas introduced to the filter through a valve 17 for the purpose of displacing the bulk of the remaining liquid contents of the filter through the leaves and into the hollow shaft 7. The remaining portion of the liquid contents of the filter shell may be drawn off from the filter shell through a drain valve 18.

Following this, the filter cake is removed from the filter leaves in the usual manner by applying to the interior of the leaves a reverse flow gas pressure. The wax cake which thus accumulates in the bottom of the shell is discharged therefrom through a valve 19.

As an example for the purpose of illustrating one mode of operation, I dissolve 1,000 gallons of wax bearing mineral oil at a temperature of 90° F. in a mixture of 1,110 gallons of acetone and 1,890 gallons of benzol and cool the solution in the chiller 2 to -10° F. to effect precipitation of 100 the solid hydrocarbons. The cooled mixture of dissolved oil and solid matter suspended therein is introduced to filter press 5, advantageously of the rotating leaf type, wherein the solvent and dissolved liquid hydrocarbons are removed 105 and a filter cake of slack wax of desired thickness is formed on the filter leaves. When the filter cake has attained the desired degree of thickness, the introduction of the filtering mixture to the filter is stopped and simultaneously 110 the introduction to the filter of fresh solvent liquid through the valve 13, consisting of acetone and benzol in the same proportion and cooled to a temperature of -10° F., is commenced, thereby maintaining a continual plus liquid pressure 115 within the filter and against the filter cake. The solvent wash liquid flows through the filter cake and filtering surfaces while the filtering element is kept in rotation, thus displacing the filtering mixture of solvent, dissolved oil and 120 solid hydrocarbons from the filter and also displacing the liquid hydrocarbons from the cake itself. The washing is kept up until a sample of the solvent wash liquid exhibits a comparative absence of dissolved liquid hydrocarbons, 125 indicating that the retained oil has been substantially completely removed from the filter cake. The introduction of solvent wash is then stopped whereupon a cool gas is admitted through the valve 17 to the filter to displace 130 the greater portion of the solvent liquid retained in the filter cake and after which the filter cake is removed from the filter.

The washed cake may then be transferred to a still wherein the solvent is removed by evaporation and recovered for further use and the solvent free wax is run to sweat pans wherein it may be sweated in the usual manner to a desired melting point or to produce wax fractions of different melting points.

All or a portion of the wash solvent liquor accumulated during the washing of the filter cake may be used as the original solvent for mixing with fresh wax bearing oil which is to undergo treatment. On the other hand, all or a portion 145 of it may be run in with the filtrate and subjected to distillation therewith to remove the solvent liquid and furnish additional low cold test oil since the wash liquid may contain substantial amounts of such oil dissolved therein. 150

The portion of the wash liquor diverted back to the filtrate is dependent upon the quantity of oil or liquid hydrocarbon dissolved therein, the wash liquor or solvent initially passing through the press, particularly during the oil displacement period, being quite rich in dissolved oil and becoming progressively leaner as washing continues, finally reaching a point where it contains substantially no dissolved oil, and at which point it may advantageously be diverted without further treatment for use in the dissolving of fresh wax bearing oil.

While in the above example I have described a dewaxing operation wherein the wax-bearing mineral oil has been mixed with a selective solvent consisting of suitable proportions of acetone and benzol, it is contemplated that the invention is equally applicable to dewaxing operations wherein other solvents, such as petroleum naphtha, for example, may be employed.

The invention is not limited to the treatment of a mineral oil such as given in the example herein, but is adapted to the treatment of other wax containing fractions of precipitates obtained from crude oils and may, for example, embrace the treatment of solid hydrocarbons contained in a slack wax produced in the manufacture of low cold test lubricating oils, and which material is an equivalent of the stock referred to in the example. Thus, while the example described advantageously sets forth one mode of operation, the invention is not restricted to any particular set of operating conditions such as that of temperature, etc., as therein described and it is, therefore, contemplated that

many modifications and variations of the invention, as hereinbefore set forth, may be made without departing from the spirit and scope thereof, and therefore only such limitations should be imposed as are indicated in the appended claim.

I claim:

In the process of manufacturing lubricating oil from wax-bearing mineral oil comprising mixing the oil with a solvent comprising acetone and benzol mixed in substantial proportions, chilling the resulting mixture to a temperature of 0° F. or lower to effect precipitation of solid hydrocarbons and introducing the chilled mixture to pressure filtering means to remove the solvent and liquid hydrocarbons and form a filter cake of solid hydrocarbons, the steps comprising introducing acetone and benzol mixed in substantially the same proportions and chilled to a temperature of 0° F. or below to the filtering means simultaneously with the cessation of flow of filtering mixture thereto, whereby the filter is maintained full of liquid and a plus liquid pressure is continuously maintained upon the filter cake throughout filtration and the subsequent cake washing step, thereby preventing fracturing or dislodgment of the cake, continuing the flow of said solvent through the cake, in situ, to remove adhering and entrained liquid hydrocarbons therefrom, and while uninterruptedly continuing the positive pressure within the filter forcing a cool gas through the washed cake to remove retained solvent liquid.
